United States Patent Office

Des. 192,387
Patented Mar. 13, 1962

192,387

BLENDER

Edward F. Hill, 97 Winthrop Road, Hillsdale, N.J.

Filed Nov. 15, 1960, Ser. No. 62,848

Term of patent 14 years

(Cl. D55—1)

Fig. 1

FIG. 2.

FIG. 3.

FIG. 4.

FIG. 1 is a perspective view of a blender showing my new design;

FIGS. 2 and 3 are top and bottom plan views, respectively;

FIG. 4 is a fragmentary perspective view of the projection and part of the adjacent area of the upper portion of the blender as shown in FIG. 1.

The other side of the blender is substantially the same as the side illustrated.

I claim:

The ornamental design for a blender, as shown and described.
